MATERIAL HANDLING MECHANISM

Edward G. Lewis, Columbus, Ohio, assignor to
The Jeffrey Manufacturing Company, a cor-
poration of Ohio

Original application August 19, 1930, Serial No.
476,390. Divided and this application April 22,
1932, Serial No. 606,995. In Great Britain
September 30, 1930

24 Claims. (Cl. 198—7)

My invention relates to loading machines of the type adapted to be transported over mine tracks in a mine and one of its objects is the provision of improved and efficient mechanism for supporting a gathering conveyor section of the loading machine for transportation along both curved and straight portions of the mine track in a mine.

A further object of the invention is the provision of improved pony truck mechanism for supporting the forward portion of a loading machine during transportation.

Other objects of the invention will appear hereinafter, the novel features and combinations being set forth in the claims hereto appended.

The present application is a division of the copending application of Levin and Lewis, Ser. No. 476,390, filed August 19, 1930, for an Improvement in material handling mechanism.

In the accompanying drawings,

Fig. 1 is a side elevation of the machine as a whole;

Fig. 2 is a side elevation of the front end of the machine on an enlarged scale;

Fig. 3 is a side elevation of the rear end of the machine on an enlarged scale;

Fig. 4 is a plan view of a medial portion of the machine;

Fig. 5 is a section on line 5—5 of Fig. 3;

Fig. 6 is a section on line 6—6 of Fig. 7;

Fig. 7 is a view of certain mechanism appearing on a smaller scale in Fig. 3;

Fig. 8 is a plan view of a pony truck forming a part of the new machine;

Fig. 9 is a side elevation of the pony truck of Fig. 8.

Referring to the drawings and particularly to

Fig. 1, A designates generally a self-propelled truck which supports a discharge conveyor B for pivotal movement about both vertical and horizontal axes, the discharge conveyor B being composed of two sections B' and B'' relatively adjustable about a transverse horizontal axis as will be described hereinafter. Pivotedly supported at the front end of the discharge conveyor B is a gathering conveyor C which, for transportation over the mine tracks, is adapted to be supported on a pony truck D, a section of mine track being shown at E.

The discharge conveyor B and its supporting truck are substantially the same as described in United States application, Serial No. 386,647, filed August 17, 1929, in the United States Patent Office, some additions and changes having been made to accommodate the unit to its present use.

Referring particularly to Figs. 3, 4, 5 and 6, the truck A comprises a frame 10 supported on wheels 11 and 12 mounted on axles 13 and 14, the wheels being designed for engagement with the mine track. Mounted on the frame 10, as shown in Fig. 5, is a platform 15 provided with an aperture 16 on whose upper margins is secured a ring 17. A frame or turntable 18 has a bottom wall 19 provided with an aperture 16 on whose upper margins is secured a ring 17. A frame or turntable 18 has a bottom wall 19 provided with an aperture in which ring 17 is engaged to form a pivotal guide for the platform. A ring 20 superposed on ring 17 overlies the margins of the aperture in wall 19 to prevent any substantial upward movement of frame 18 relative to the platform 15.

A motor 21 is mounted on frame 18 with its armature shaft extending transversely thereof, the armature shaft having secured thereon a sprocket 22 which through a chain 23 drives a sprocket 24 mounted on a shaft 25 parallel to the armature shaft. The upper run of chain 23 is engaged by an idler pulley 26 as shown in Fig. 3. At its end opposite sprocket 24, shaft 25 has fixed thereto a second sprocket which engages a chain 27 (Fig. 5) to drive a sprocket 28, fixed to a hub 29, which is freely revoluble on a shaft 30 journaled in the upper portion of frame 18 in parallel relation to shaft 25. A shiftable clutch element 31 is splined on shaft 30 and is provided with teeth 32 adapted to engage teeth 33 formed on hub 29 so that the rotation of the latter may be imparted to shaft 30. Fixed on shaft 30 within and adjacent the side walls of frame 18 is a pair of sprockets 34 and 35 which are adapted to engage the lower runs of chains 36 and 37 which traverse the full length of the discharge conveyor B and are inter-connected by means of material engaging flights 38.

A shaft 39 is journaled in frame 18 below shaft 30 and parallel thereto. Hub 29 has formed thereon a sprocket 40 connected by means of a chain 41 with a sprocket 42 fixed in the end of shaft 39. Freely revoluble on shaft 39 directly above aperture 16 is a sheave 43 with which is engaged a universally flexible chain 44 which is passed downwardly through aperture 16 and thence forwardly and rearwardly around sheaves 45 and 46 in engagement with sheaves as at 47 fixed to axles 13 and 14. Sheave 43 has formed thereon clutch teeth 48 adapted to be engaged by clutch teeth 49 formed on a shiftable clutch member 50 splined on shaft 39. Thus when shaft 39 is driven and clutch teeth 48 and 49 are

engaged, wheels 11 and 12 will be driven through chain 44, the drive being effective throughout a considerable range of angular adjustment of frame 18 relative to the platform 15 due to the 5 universal flexibility of the chain 44.

One end of shaft 39 is journaled in a sleeve bearing 51 fixed in frame 18. Inwardly of this bearing, shaft 39 has fixed thereon a housing 52 for a thrust bearing 53 which is interposed between the housing and the inner end of bearing 51. Splined on the end of shaft 39 outwardly of the bearing 51 is a cone-faced friction clutch member 54. Engaged co-axially in member 54 is a screw threaded nipple 55 which at its inner end is adapted to bear against the end of shaft 39. A cap screw 56 passes through nipple 55 and is threaded in a bore in the end of shaft 39 to prevent axial displacement of the nipple relative thereto. By loosening the cap screw and turning the nipple relative to shaft 39, element 54 may be adjusted longitudinally of the shaft and when the proper adjustment has been obtained, the nipple may be locked by tightening the cap screw.

25 Freely revoluble on shaft 39 between bearing 51 and clutch element 54 is a winding drum 57 having formed thereon a conical flange 58 adapted to cooperate with clutch element 54, a cylindrical brake flange 59 being provided at the other side of the drum. Inferiorly of flange 59 is a radial flange 60 engaged with a slight lost motion in an annular groove 61 formed in a sleeve 62 revolvably mounted on the outer end of bearing sleeve 51. Engaged between an inwardly projecting radial rib 63 of sleeve 62 and the adjacent end of drum 57 is a thrust bearing 64.

Sleeve 62 is provided with diametrically opposite studs 65 and 66 engaged in the slotted ends of arms 67 and 68 of a shipper member which is pivoted on a pin 69. Mounted parallel to pin 69 in bearings 70 and 71 and on the opposite side of shaft 39 is a rocking shaft 72 having at its lower end an eccentric pin 73 engaged in the slotted end of a prolongation 68' of arm 68. A lever 74 is fixed to the upper end of shaft 72, and intermediate the bearings 70 and 71 a torsion spring 75 surrounds the shaft, one end of the spring being secured to bearing 71 and the other end to a washer 76 which is fixed to the shaft. When shaft 72 is rocked in a clockwise direction, the shipper member is swung against the action of spring 75 to move the winding drum through the intermediary of thrust bearing 64 to engage the external friction clutch element 58 with the internal element 54 to cause rotation of the winding drum with shaft 39. Bearing 53 carries the thrust thus imposed on shaft 39. Upon release of lever 74, spring 75 causes the disengagement of the clutch elements due to the engagement of flange 60 in groove 61 of the shipper-controlled sleeve 62.

Journalized in a bracket 76 in parallel relation to shaft 39 is a pin 77 on which is oscillably mounted a lever 78. A brake band 79 has one of its ends secured to pin 77 and passes thence around brake flange 59 of drum 57, the other end of the band terminating in a lug 80. Lever 78 (Fig. 6) has integral therewith a bracket-like portion 78', this portion and the lever proper supporting a pin 81 in parallel spaced relation to pin 77. An eye bolt 82 is engaged by pin 81 and has its threaded shank portion passed through an aperture formed in lug 80. Between lug 80 and a nut 83 at the end of the eye bolt is interposed a compression spring 84, an abutment nut

85 being screwed on the shank of the eye bolt to the other side of lug 80 from spring 84. Adjustment of eye bolt 82 and spring 84 is obtained through adjustment of nuts 83 and 85. A torsion spring 86 surrounds pin 77 at one side of lever 78, one of its ends engaging the bottom of bracket 76 and the other engaging pin 81 as shown in Fig. 7.

5 Adjacent the upper end of lever 78, a number of teeth 87 are formed, these being engageable by a pawl 88 mounted on a pin 89. At its extreme upper end, lever 78 is provided with a handle 90 projecting in parallel relation to pin 77.

10 With pawl 88 disengaged from teeth 87, brake band 79 is released through the action of spring 86. When lever 78 is swung in a counter-clockwise direction, the band is tightened with a cushioned effect due to spring 84, it being understood that tension is applied to the band through this spring. Pawl 88 may be thrown in cooperative relation to teeth 87 to maintain the brake band 20 taut. In any event, when lever 78 is released, spring 86 acts to loosen the band and thus release the winding drum. Inasmuch as the brake flange 59 is axially shiftable with drum 57, the flange is made of sufficient width so as to be always in 25 full cooperative relation with band 79.

From the above description, it will be seen that 30 motor 21 is adapted to drive the conveyor chains 36 and 37 when the clutch teeth 32 and 33 are engaged and is adapted to drive the truck wheels and the winding drum through shaft 39 when the clutches 48, 49 and 54, 58 are engaged. While 35 all the power trains may be driven simultaneously, if such operation should, by chance, become necessary, the important point is that each of the three drives may be effected entirely independently. However, simultaneous operation of the conveyor and drum drives is an essential feature in the loading operation of the machine, as will 40 hereinafter appear, and this, of course, is effected by the engagement of clutches 32, 33 and 54, 58. Further, simultaneous drive of the truck wheels and the winding drum is desirable as when it is desired to assist the machine up an incline by means of a tension member engaged 45 with the drum. As another important possibility, when negotiating a decline, the motor may be shut off and, clutches 48, 49 and 54, 58 being engaged, brake band 79 may be tensioned to 50 brake the truck wheels.

55 Referring to Figs. 1 and 3, it will be noted that the adjacent portions of conveyor sections B' and B'' constitute an inclined portion having at its upper end a substantially horizontal prolongation and at its lower end another substantially horizontal extension adjacent the mine track. To each side of section B'', and at its upper end is attached an arm of which one is shown at 91 (Fig. 3), the arms extending along the adjacent end of conveyor section B' and supporting 60 a pin 92 upon which section B' is oscillably mounted. Each arm 91 has a threaded rod 93 pivoted to its extremity, each rod being provided at its end with a nut 94 and being engaged in an aperture in a bolster 95 which extends beneath 65 section B'. Each rod 93 has a compression spring 96 mounted thereon between the bolster and nut. Section B' is thus resiliently supported on bolster 95 and its position relative to section B'' may be 70 adjusted as desired by appropriate adjustment of nuts 94. The conveyor as a whole is supported for movement about shaft 30 so that its lower end may rest upon the track E or may be elevated for transportation. An apron 103 is so disposed as to guard the lower runs of the conveyor 75

veyor chains from interference with the underlying parts of the machine.

At the forward end of the inclined conveyor portion are secured plates 97 and 98 each of which has a forward horizontal portion extending transversely of the conveyor and provided with a plurality of apertures as at 99 and 100, in which may be engaged pins 101 and 102 to project below the shoes into lateral engagement with the track rails to prevent lateral displacement of the conveyor. At its rear end, plate 97 supports a pair of sheaves 104 and 105 on substantially upright axes while plate 98 similarly supports a sheave 106.

Supported between upright arms 107 and 108 is a panel 109 upon which are arranged the various electrical control appliances. Arm 108 also revolvably supports at its upper end a sheave 110 on a horizontal axis and spaced inwardly of the sheave (Fig. 4), the arm is provided with parallel jaws 111. Directly opposite arm 108 a sheave 112 is revolvably mounted on a bracket 113 on an upright axis.

To the forward end of conveyor section B'' is pivoted on a pivot member 114 disposed on the central longitudinal line of the conveyor section, a bracket or mounting member 115 comprising angular sections 116 and 117. The bracket is capable of swinging from one side of the forward end of section B'' to the other. A horizontal angle bar 118 secured adjacent the extremity of bracket portion 117 has a depending lug 119 adapted to engage behind an arcuate rail 120 formed on a flange 121 secured to the conveyor section end, rail 120 having pivot member 114 as its center. Extending transversely of the upper end of portion 117 opposite angle bar 118 is a channel member 122, while at the lower extremity of portion 117 is fixed a shoe 123.

As may be seen most clearly from Fig. 2, the gathering conveyor C comprises a normally horizontal portion C' and an inclined portion C''. A base plate 124 extends throughout conveyor C and has disposed thereon suitable guide members as at 125 for an endless conveyor chain 127 flexible both horizontally and vertically. The conveyor chain is adapted to advance along one side of plate 124 and return along the other. Flights 128 attached to the chain at intervals are adapted to engage material and move it along the base plate and discharge it from the upper extremity of the inclined section. Flights 128 are freely exposed laterally on portion C' of conveyor C, material retaining side walls 129 and 130 being provided along the inclined edges of section C''.

The conveyor head shaft 131 has a sprocket fixed thereto and engaging chain 127 to drive the latter, a foot sprocket being arranged on shaft 132. Also fixed on shaft 131 is a bevel gear 133 engaged by a drive pinion 134 which in turn is driven from the armature shaft of a motor 135 mounted on a suitable base supported on plate 124 intermediate the runs of chain 127. Extending forwardly from motor 135 and centrally of plate 125 is an upright baffle board 136 at the extremity of which is an upright post 137 provided with an aperture 138 and a bifurcated extremity 139.

Adjacent head shaft 131 plate 124 has secured thereto a bracket having spaced side walls of which one is shown at 140 (Fig. 2) projecting downwardly and adapted to receive channel 122 between them. Walls 140 are perforated to receive a removable pin 141 which is adapted to ex-

tend through channel 122 to unite the gathering conveyor C with mounting member 115, already described.

It will be evident that conveyor C may be adjusted relative to conveyor B about an axis defined by pivot member 114 and about a horizontal axis defined by pin 141. Due to the spaced relation of pin 141 to the top and bottom walls of channel 122, conveyor C may also be adjusted relative to conveyor B about a longitudinally extending axis. The upper end of conveyor C is normally supported on the upper end of bracket portion 117 on a rocking block or bolster 142.

In operation, portion C' of the gathering conveyor C assumes the position shown in Fig. 2 wherein it is adapted to rest directly on the mine floor and to be swung thereover in the manner which has been described in my application first mentioned above. When the machine is to be transported, however, the gathering conveyor is supported on the pony truck D as shown in Fig. 1.

The pony truck D, as most clearly shown in Figs. 8 and 9, comprises a pair of axles 143 and 144 upon which are mounted wheels 145 and 146, the axles being joined by means of a frame 147 composed of angle bars of sufficient width to bring their top surfaces substantially to the tops of the wheels 145 and 146. Exactly centrally of frame 147 is mounted a vertical pin 148 having a rounded extremity and concentrically with the pin is mounted a ring 149 of relatively large diameter. Struts 150 and 151 are interposed between the overhanging ring portions and axles 143 and 144, while struts 152 and 153 are interposed between the axles and the central member 141. Adjacent the lower extremity of portion C'' of the gathering conveyor is fixed an inverted cup-like member 154 on the central longitudinal line of the conveyor.

When the machine is to be moved about the mine, the gathering conveyor is tilted about pin 141, the pony truck placed thereunder and pin 148 engaged in cup 154. Pin 148 is of such height as would enable it to support the gathering conveyor with portion C'' thereof spaced above ring 149 in parallel relation to the plane of the latter. However, due to the disposition of cup 154 relative to the length of conveyor C the forward portion of the latter overbalances the rear portion, elevating the forward end of conveyor B through the described connection and bringing the parts to the position shown in Fig. 1, plate 124, forward of cup 154, resting on ring 149. Thus in transporting the machine, the weight of conveyor C and of the forward end of conveyor B is divided between pin 148 and ring 149, this relation being maintained in all angular positions of conveyor C relative to the truck.

Inasmuch as the gathering conveyor is of considerable weight, it is desirable to provide motor operated means for elevating it into such position as to enable the pony truck to be placed thereunder. A casting 155 secured to base plate 124 forwardly of head shaft 131, has a pair of spaced upwardly projecting ears 156 and 157 which support a pin 158 which extends transversely of the plate, see Figs. 2 and 4. A member 159 comprising two parallel arms is pivoted at one end on pin 158 and at its other end has a bail 160 pivoted thereto by means of a pin 161. A cable 162 secured to the bail is passed forward through aperture 138 of post 137 and secured, the cable when taut permitting member 159 to take the position shown in Fig. 2. Intermediate the upper ends of the arms comprising

member 159 a block 163 is mounted on pin 161, this block revolvably supporting a pair of sheaves 164 and 165. A tubular member 166 is pivoted at 167 to a casting on the motor frame and projects rearwardly between the arms of member 159. Forwardly of member 159, member 166 is provided with a downwardly projecting longitudinally slotted web 168 in the slot of which is engaged a removable pin 169 extending between and supported by the arms of member 159. Abutment of pin 169 with the lower end of the slot of web 168 serves to hold member 159 in the upright position of Fig. 2 and also serves to hold member 166 in the position shown in Fig. 2, members 159 and 166 thus acting as mutual props.

Referring to Figs. 1 to 4, a rope or cable 170 is adapted to have one of its ends engaged with drum 57. Thence the cable is adapted to be trained forwardly over sheave 110, thence around sheaves 165, rearwardly to and around sheave 112, again forwardly and around sheave 164, and finally rearwardly again to be anchored between jaws 111. It will be evident that upon rotation of drum 57 in the winding direction and consequent tensioning of rope 170, a substantially horizontally directed pull will be exerted on conveyor C above pivot pin 141 due to the attachment of block 163, which supports sheaves 164 and 165 to the upper end of member 159. Tensioning of cable 162 arresting any tendency of member 159 to swing about pin 158, it will be evident that the forward end of conveyor C will be swung upwardly. After the pony truck has been placed as has been above described, the tension on rope 170 may be released.

The controller for motor 135 is disposed on panel 189 and novel means are provided for supporting the electrical conductors intermediate the controller and the motor.

Vertically reciprocable in bearings 171 and 172 on upright 107 is a tubular member 173 having a horizontal projecting upper extension 174 whose extremity is outwardly flared. Conductor cable 45 175 is trained through the tubular housing constituted by portions 173 and 174 and thence is passed through tubular member 166 to the motor, the free extremity of member 166 being outwardly flared. During operation of the gathering conveyor it is desired that the cable portion intermediate the two tubular supports be elevated so as not to interfere with the passage of material from one conveyor to the other and such disposition is illustrated in Figs. 2 and 3, 50 member 166 being maintained in the position shown by the means already described. Bearing 171, on the other hand, is provided with a recess 176 adapted to be engaged by a lug 177 on tubular member 173, the lug, when so positioned, being engageable by a latch 178 hung on bearing 171. It will be evident that the walls of the recess 176 engaging the lug prevent rotation of element 173 and thereby prevent accidental disengagement 60 of the lug from the latch, the latter serving to hold the tubular guide element in the position of upward adjustment shown in Fig. 3.

When the machine is to be transported, latch 178 is swung to release lug 177, whereupon guide member 173 drops to the position shown in Fig. 1 wherein it is arrested due to engagement of lug 177 with the bearing 172. Removal of pin 169 from the slot of web 168 permits member 159 to swing forwardly and somewhat downwardly and at the same time permits member 166 to swing

downwardly, thereby considerably decreasing the height of the machine as a whole.

Various maneuvering possibilities of the machine for the purpose of gathering material have been described in the application first mentioned above and need not be repeated here. Attention may merely be called to the fact that rope 170, due to the stud mounting of sheaves 110, 112, 164 and 165, may be quickly dismounted therefrom and engaged with sheaves 104 or sheaves 105 and 106 to effect swinging of the gathering conveyor. 5 10

It should be particularly noted that the hoisting mechanism for elevating the gathering conveyor above the track to provide space for the pony truck to be moved under the same is below the upper horizontal plane extending through the top of the discharge conveyor B. It will also be seen that when the hoisting mechanism lets the gathering conveyor C descend so that the cup 154 fits over the pin 148 the overbalanced weight of the gathering conveyor in advance of the pin 148 will effect the lifting of the conveyor section B'' to clear the mine track for transportation as shown in Fig. 1. The tension on the ropes or cables 162 and 173 may be entirely relieved during transportation because the ring 149 coacts with the pin 148 to support the gathering conveyor not only on straight portions of the mine track but also on curves. During transportation around curves of the mine track the gathering conveyor slides arcuately on the ring 149 while pivoting on the upright axis of the pin 148, and at the same time there is a relative swinging of the conveyors B and C on the upright axis at 114. 30 When the loading machine illustrated in Fig. 1 travels around curves in the mine track the discharge conveyor B will swing on the upright axis at 16, 17, 20 (Fig. 5), the conveyors B and C will swing on the upright axis at 114, and the conveyor C will swing on the upright axis at 148, while the loose connection between the conveyors at 141 permits the bottom of the gathering conveyor C to keep firmly seated on the supporting ring 149.

49. Obviously those skilled in the art may make 45 various changes in the details and arrangement of parts without departing from the spirit and scope of the invention as defined by the claims hereto appended and I wish therefore not to be 50 restricted to the precise construction herein disclosed.

Having thus described and shown an embodiment of my invention, what I desire to secure by Letters Patent of the United States is:

1. In a machine of the class described, the combination with a truck, of an elongated conveyor mounted on said truck for pivotal movement relative thereto about a horizontal axis, the receiving end of said conveyor overbalancing its delivery end, a gathering conveyor having its delivery end pivoted to the receiving end of said first-named conveyor for movement relative thereto on a horizontal axis, a supplemental truck adapted to be placed under said gathering conveyor when the latter is elevated, and means comprising a pin and cup between the gathering conveyor and said supplemental truck when the latter is so placed, said pin and cup being located relative to the center of gravity of said gathering conveyor to cause the receiving end of the latter when released to overbalance its delivery end and thus rock said gathering conveyor about its truck engaging means to elevate the delivery end of 75

said gathering conveyor together with the receiving end of said elongated conveyor.

2. In loading apparatus, the combination with a support, of an elongated conveyor mounted thereon with the receiving end of said conveyor adjustable in elevation, a gathering conveyor connected to said elongated conveyor, and a supplemental arcuate support for said gathering conveyor at a point to cause an overbalanced portion of the gathering conveyor to elevate the receiving end of said elongated conveyor.

3. In loading apparatus, the combination with a main truck adapted to travel on a mine track, of an elongated conveyor mounted thereon with its receiving end adapted to be varied in elevation, a gathering conveyor connected to the receiving end of said elongated conveyor, a ring pony truck for supporting said gathering conveyor in elevated position, and connecting mechanism between said pony truck and the bottom of said gathering conveyor at a point to cause a forward overbalanced portion of said gathering conveyor to elevate the receiving end of said elongated conveyor.

4. In a machine of the class described, a conveyor line comprising two horizontally extending sections pivoted together on a transverse horizontal axis, a wheel mounted base supporting one of said sections and a pony truck for supporting the other of said sections, there being supporting means between said pony truck and said other of said sections comprising a disengageable thrust and pivot bearing permitting relative swinging of the pony truck and the section supported thereby on a vertical axis and universal tilting on horizontal axes, and a horizontal ring mounted on said pony truck in concentric relation with said bearing and in a position above the remaining truck structure externally of the ring, the pony truck supported section having a bottom inclined over the pony truck and slidably supported on said ring, said inclined bottom extending beyond the ring and substantially below the top plane thereof.

5. In a machine of the class described, a conveyor line comprising two horizontally extending sections pivoted together on a transverse horizontal axis, a wheel mounted base supporting one of said sections and a pony truck for supporting the other of said sections, there being supporting means between said pony truck and said other of said sections comprising a disengageable thrust and pivot bearing permitting relative swinging of the pony truck and the section supported thereby on a vertical axis and universal tilting on horizontal axes, and a horizontal arcuate bar mounted on one end of said pony truck and extending transversely of the latter in concentric relation with said bearing and free of external obstruction throughout a substantial vertical extent below the bar, the pony truck supported section having a bottom inclined over the pony truck and slidably supported on said bar, said inclined bottom extending beyond the bar and substantially below the top plane thereof.

6. In a machine of the class described, a conveyor line comprising two horizontally extending sections pivoted together on a transverse horizontal axis, a wheel mounted base supporting one of said sections and a pony truck for supporting the other of said sections, there being supporting means between said pony truck and said other of said sections comprising a disengageable thrust and pivot bearing permitting relative swinging of the pony truck and the sec-

tion supported thereby on a vertical axis and universal tilting on horizontal axes, and a horizontal ring mounted on said pony truck in concentric relation with said bearing pivot above the pony truck wheels and projecting forwardly and rearwardly beyond the remainder of the pony truck structure so that the front and rear portions of the ring are free of external obstruction throughout a substantial vertical extent below the ring, the pony truck supported section having a bottom inclined over the pony truck and slidably supported on said ring, said inclined bottom extending beyond the ring and substantially below the top plane thereof.

7. In a machine of the class described, a conveyor line comprising two horizontally extending sections pivoted together on a transverse horizontal axis, a wheel mounted base supporting one of said sections and a pony truck for supporting the other of said sections, there being supporting means between said pony truck and said other of said sections comprising a disengageable thrust and pivot bearing permitting relative swinging of the pony truck and the section supported thereby on a vertical axis and universal tilting on horizontal axes, and a horizontal arcuate bar mounted on one end of said pony truck and extending transversely thereof in concentric relation with said bearing above the pony truck wheels and projecting outwardly beyond the remainder of the pony truck structure so that the bar is free of external obstruction throughout a substantial vertical extent below the bar, the pony truck supported section having a bottom inclined over the pony truck and slidably supported on said bar, said inclined bottom extending beyond the bar and substantially below the top plane thereof.

8. A pony truck comprising a wheel supported frame, a horizontal ring mounted on said frame in a position above the remaining truck structure externally of the ring, and a pivot member on said frame centrally of said ring, said ring being adapted to support slidably a frame sloped across the plane of said ring to project therebelow and pivotal about said pivot member on a vertical axis.

9. A pony truck comprising a wheel supported frame, a horizontal ring mounted on said frame in a position above the remaining truck structure externally of the ring, and a pivot member on said frame centrally of said ring, the ring projecting forwardly and rearwardly beyond the ends of the truck frame, said ring being adapted to support slidably a frame sloped across the plane of said ring to project therebelow and pivotal about said pivot member on a vertical axis.

10. A pony truck comprising a wheel supported frame, a horizontal arcuate bar mounted on one end of said frame in a position above the remaining truck structure outwardly of said bar, and a pivot member on said frame at the center of the arc on which said bar extends, said bar being adapted to support slidably a frame sloped across the plane of said bar to project therebelow and pivotal about said pivot member on a vertical axis.

11. A pony truck comprising a wheel supported frame, a horizontal arcuate bar mounted on one end of said frame in a position above the remaining truck structure outwardly of said bar, and a pivot member on said frame at the center of the arc on which said bar extends, the bar being above the truck wheels and projecting outwardly beyond the end of the truck frame on which it is

- mounted, said bar being adapted to support slid-
ingly a frame sloped across the plane of said bar
to project therebelow and pivotal about said pivot
member on a vertical axis.
- 5 12. In a machine of the class described, the
combination with a truck adapted to travel on
a mine track, of an elongated discharge conveyor
mounted on said truck and pivoted thereto on
10 vertical and horizontal axes, the receiving end of
said conveyor overhanging the truck and extend-
ing downwardly in proximity to the track, a gath-
ering conveyor having its delivery end pivoted to
the receiving end of said discharge conveyor on
15 vertical and horizontal axes, a pony truck and a
universal joint between said pony truck and said
gathering conveyor to afford a support for the
gathering conveyor on said pony truck while per-
mitting the gathering conveyor to tilt either longi-
tudinally or laterally relative to the pony truck.
- 20 13. In a machine of the class described, the
combination with a truck adapted to travel along
a mine track, of an elongated conveyor mounted
on said truck and pivoted thereto on an upright
axis, the receiving end of said conveyor overhang-
25 ing the truck and extending downwardly in prox-
imity to the track, a gathering conveyor having
its delivery end pivoted to the receiving end of
said first-named conveyor on an upright axis,
an additional truck, and means for supporting
30 said gathering conveyor on said additional truck
with universal tilting movement between the
gathering conveyor and said additional truck.
- 35 14. In a machine of the class described, the
combination with a truck adapted to travel over
a mine track, of an elongated conveyor mounted
on said truck, a gathering conveyor having its de-
livery end pivoted to the receiving end of said
40 first-named conveyor for movement relative
thereto on upright and horizontal axes, a sup-
plemental truck, a universal joint between said
supplemental truck and said gathering conveyor,
and an abutment on the supplemental truck for
45 limiting the movement of the gathering conveyor
relative to said supplemental truck.
- 45 15. In a loading apparatus, the combination
with a truck adapted to travel along a mine track,
of an elongated conveyor mounted thereon, gath-
ering mechanism adapted to gather material from
50 the mine floor in advance of the mine track, a
pony truck, a universal joint between said pony
truck and said gathering mechanism, and an
arcuate abutment serving as a track upon which
55 said gathering mechanism may slide when the
loading apparatus is traveling along a curved por-
tion of said mine track.
- 60 16. In a machine of the class described, the
combination with a truck, of an elongated con-
veyor mounted on said truck for pivotal move-
ment relatively thereto about a horizontal axis,
the receiving end of said conveyor over-balanc-
65 ing its delivery end, a gathering conveyor hav-
ing its delivery end pivoted to the receiving end
of said first-named conveyor for movement relative
thereto on a horizontal axis, a sup-
plemental truck adapted to be placed under said
70 gathering conveyor when the latter is elevated,
a universal joint for connecting said supplemental
truck to said gathering conveyor when said sup-
plemental truck is placed under said gather-
ing conveyor, said universal joint being located
75 relative to the center of gravity of said gather-
ing conveyor to cause the receiving end of the
latter when released to overbalance its delivery
end and thus rock said gathering conveyor about
said universal joint as a fulcrum to elevate the
- delivery end of the gathering conveyor to-
gether with the receiving end of said elongated
conveyor.
17. In loading apparatus, the combination with
a support, of an elongated conveyor mounted
thereon with the receiving end of said conveyor
adjustable in elevation, a gathering conveyor con-
nected to said elongated conveyor, and a sup-
plemental support having a universal joint for
connection to said gathering conveyor at a point
10 to cause an overbalanced portion of the gather-
ing conveyor to elevate the receiving end of said
elongated conveyor.
18. In loading apparatus, the combination with
a main truck adapted to travel on a mine track,
15 of an elongated conveyor mounted thereon with
its receiving end adapted to be varied in eleva-
tion, a gathering conveyor connected to the re-
ceiving end of said elongated conveyor, a pony
truck for supporting said gathering conveyor in
20 elevated position, and a universal joint between
said pony truck and the bottom of said gathering
conveyor at a point rearward of the center of
gravity of said gathering conveyor to cause a for-
ward overbalanced portion of said gathering con-
veyor to elevate the receiving end of said elon-
gated conveyor.
- 25 19. In loading apparatus, the combination with
a truck adapted to travel along a mine track, of
an elongated conveyor pivotally connected to
30 said truck for movement relative thereto on a
horizontal axis, a gathering conveyor pivoted to
the receiving end of said elongated conveyor, a
pony truck for supporting said gathering con-
veyor in elevated position for transportation along
35 said mine track, and a universal joint between
said pony truck and said gathering conveyor to
support the latter for longitudinal and lateral
tilting movements relatively to said pony truck
with the center of gravity of the gathering con-
40 veyor forward of said universal joint to cause the
forward portion of said gathering conveyor to
move downwardly on such universal joint and ef-
fect elevation of the receiving end of said elon-
gated conveyor by the pivotal connection between
45 the conveyors when said gathering conveyor is
loaded on said pony truck.
- 50 20. In loading apparatus, the combination with
a truck adapted to travel along the mine track,
of an elongated conveyor pivotally mounted on
55 said truck on a horizontal axis with the receiv-
ing end of said elongated conveyor variable in ele-
vation, a gathering conveyor pivoted to the re-
ceiving end of said elongated conveyor, a pony
truck for supporting said gathering conveyor, a
60 connection between said pony truck and said
gathering conveyor at a point rearward of the
center of gravity of said gathering conveyor to
effect movement of the receiving end of said
elongated conveyor to an elevated position when
65 said gathering conveyor is supported on said pony
truck, and a track mounted on said pony truck in
position to limit the downward movement of the
forward portion of said gathering conveyor and the
upright movement of the receiving end of
70 said elongated conveyor when said gathering con-
veyor is mounted on said pony truck.
- 75 21. In loading apparatus, the combination with
a truck adapted to travel along a mine track, of
an elongated conveyor mounted on said truck
with the receiving end thereof adjustable in eleva-
tion, a gathering conveyor connected to said
elongated conveyor, means on the receiving end
of said first-named conveyor for supporting such
receiving end on the mine track during operation

of said gathering conveyor in advance of the mine track, means for operating said gathering conveyor in advance of the mine track, a pony truck for supporting the gathering conveyor in elevated position during transportation along said mine track, and a positioning device comprising a universal joint between said pony truck and said gathering conveyor in such position as to cause the forward overbalanced portion of said gathering conveyor to effect lifting of the receiving end of said first-named conveyor clear of the mine track for transportation.

22. In loading apparatus, the combination with a truck adapted to travel along a mine track, of an elongated conveyor pivotally connected to said truck for movement relative thereto on a horizontal axis, a gathering conveyor pivoted to the receiving end of said elongated conveyor, a pony truck for supporting said gathering conveyor in elevated position for transportation, a connection between said pony truck and said gathering conveyor for relative movement on a transverse horizontal axis at a point rearward of the center of gravity of the gathering conveyor to cause the forward portion of said gathering conveyor to move downwardly on said horizontal axis and for elevation of the receiving end of said elongated conveyor through the pivotal connection between the conveyors, and means on said pony truck forwardly of said connection for engagement by the forward portion of said gathering conveyor to limit its downward movement.

23. In loading apparatus, the combination with a truck adapted to travel along a mine track, of an elongated conveyor pivotally connected to said truck for movement relative thereto on horizontal and vertical axes, a gathering conveyor pivoted to the receiving end of said elongated

conveyor on a horizontal axis, a pony truck for supporting said gathering conveyor in elevated position for transportation, a connection between said pony truck and said gathering conveyor providing vertical and horizontal swinging axes for said conveyor at a point rearward of the center of gravity of the gathering conveyor to cause the forward portion of said gathering conveyor to move downwardly on the last-named horizontal axis and effect elevation of the receiving end of said elongated conveyor through the pivotal connection between the conveyors, and an arcuate abutment on said pony truck in advance of said connection for slidably supporting the forward portion of said gathering conveyor.

24. In loading apparatus, the combination with a truck adapted to travel along a mine track, of an elongated conveyor pivotally connected to said truck for movement relative thereto on horizontal and vertical axes, a gathering conveyor pivoted to the receiving end of said elongated conveyor on a horizontal axis, a pony truck for supporting said gathering conveyor in elevated position for transportation, a connection between said pony truck and said gathering conveyor providing vertical and horizontal swinging axes for said conveyor at a point rearward of the center of gravity of the gathering conveyor to cause the forward portion of said gathering conveyor to move downwardly on the last-named horizontal axis and effect elevation of the receiving end of said elongated conveyor through the pivotal connection between the conveyors, and a ring on said pony truck concentric with said connection for slidably supporting the forward portion of said gathering conveyor.

EDWARD G. LEWIS.
